[57] **CLAIM**

The ornamental design for a cuticle pusher blade, as shown and described.

DESCRIPTION

FIG. 1 is a perspective view of a cuticle pusher blade showing my new design in full lines with the broken line showing of the handle being for illustrative purposes only and forming no part of the claimed invention;
 FIG. 2 is a top plan view of the pusher blade per se;
 FIG. 3 is a right side elevational view thereof, the left side view being a mirror image of the right side view;
 FIG. 4 is a bottom plan view thereof;
 FIG. 5 is a front elevational view thereof; and,
 FIG. 6 is a rear elevational view thereof.

FIG. 2

FIG. 1

FIG. 4

FIG. 3

FIG. 5
